C. L. LONSINGER

WALKING BEAM

Filed May 4, 1927

UNITED STATES PATENT OFFICE.

CHARLES L. LONSINGER, OF WALHONDING, OHIO.

WALKING BEAM.

Application filed May 4, 1927. Serial No. 188,741.

The invention relates to walking beams, and has for its object to provide a device of this character with cushioned truss rods, whereby shock and jar incident to the operation of the device are absorbed, thereby insuring an easy operation and a beam which will have a flexible springing motion, consequently breaking of the drilling rope is obviated.

10 A further object is to provide the under portions of the end of the beam with transverse plates anchored in recesses thereof, and extending beyond the opposite sides of the beam, and to which plates the ends of the 15 truss rods are anchored, thereby positively anchoring the truss rod ends to the ends of the beam. Also to provide the inner sides of the plates with inwardly extending ribs engaging in channels in the beam ends for 20 additionally anchoring the plates against displacement.

A further object is to provide the upper side of the beam with an upwardly extending dome terminating in a cap plate, through 25 which vertical rod ends extend and cooperating link members on the cap plate, at opposite sides of the vertical rod ends, and to which the adjacent ends of the truss rods are anchored. The link members being adjustable 30 in relation to each other whereby the tension of the truss rods may be varied.

A further object is to interpose between the dome and the cap plate a resilient member, for instance a rubber cushion, which is compressed by the cap plate, incident to strain thereon for allowing a springing action of the beam within the limits of the truss rods.

A further object is to form the dome from adjacent cylindrical members supported on 40 the beam, and through which the vertically disposed rods extend, a plate on the upper end of the cylindrical members, and which plate is held in close engagement with the upper end of the cylindrical members by 45 means of nuts on the vertically disposed rods, a plate having nut receiving apertures therein, and through which the vertically disposed rods extend, and which prevents rotation of the nuts, a plate engaging the upper side of 50 the nut holding plate and on which the resilient member is disposed and a convexed crown plate on the top of the last named plate, which crown plate is preferably upwardly convexed.

A further object is to provide the upper 55 sides of the ends of the beam with plates for

the reception of the rod rope end and the rig loop, which plates have in connection therewith yieldable means for additionally taking up the shock incident to the operation of the device.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of the walking beam.

Figure 2 is a top plan view of the walking beam.

Figure 3 is a vertical transverse sectional view through the walking beam taken on line 3—3 of Figure 2.

Figure 4 is a horizontal sectional view through the dome taken on line 4—4 of Figure 3.

Figure 5 is a bottom perspective view of one of the walking beam ends.

Figure 6 is a perspective view of one of the transverse plates.

Referring to the drawing the numeral 1 designates the body of the walking beam which is wider at its central point than at its ends and is adapted to rock on any suitable supporting means at the point *a*. Extending upwardly through the beam 1 centrally thereof and in transverse relation are spaced vertically disposed rods 2, which rods are preferably provided with heads 3 disposed in recesses 4 in the under sides of the beam 1. Disposed on the upper side of the beam 1 is a base plate 5, on which rest the lower ends of vertically disposed cylindrical members 6, which cylindrical members are bolted together by means of bolts 7 for preventing displacement in relation to each other. Disposed on the upper end of the cylindrical members 6 is a transverse cap plate 8, and it will be noted that the vertically disposed rods 2 extend upwardly through the beam 1, base plate 5, cylinders 6 and cap plate 8, and provided with threaded ends 9 on which are threaded nuts 10, which when tightened against the cap plate 8, forces the cap plate into close binding engagement with the upper ends of the cylinders 6 and force said cylind-

ders downwardly into close binding engagement against the plate 5, which in turn is forced into binding engagement with the upper side of the beam 1, thereby forming a rigid dome structure. Disposed on the upper side of the cap plate 8 is a filler plate or block 11, which is preferably formed from wood or other fibrous material, and is provided with apertures 12 conforming substantially to the shape of the nuts 10, and not only serves to add strength and a slight resiliency but also as means for preventing retrograde rotation of the nuts 10 after they have been adjusted to proper tension, therefore it will be seen that after the nuts 10 have been adjusted and the parts assembled, that loosening of the nuts is obviated.

Disposed on the upper side of the filler member 11 is a plate 13, which forms a bed or seat for a resilient member 14 which is preferably formed from rubber whereby a yielding and extending action is insured for the transversely disposed crown plate 16, which crown plate is transversely bent and has its opposite ends 17 in engagement with the resilient member 14, whereby there will be a springing action of the crown plate 16. The threaded rods 2 extend upwardly through the plate 13, resilient member 14 and crown plate 16 and may be provided with nuts 17^a if desired, the purpose of which will be presently described.

The under sides of the outer ends of the beam 1 are provided with angled portions 18 having transverse recesses 19 therein and disposed in said recesses 19 are transverse plates 20, which plates are provided with V-shaped ribs 21, which are received in the V-shaped recesses 22 in the bottoms of the recesses 19, thereby positively preventing displacement of the plates. Plates 20 are preferably provided with apertures 23 for the reception of securing means. The ends of the plates 20 extend beyond the opposite sides of the beam 1 and are provided with apertures 24 which receive therein the ends 25 of the truss rods 26, and which truss rods incline upwardly and inwardly and terminate in eyes 27, through which extend the arms 28 of the right angled shaped links 29, and which links have one of their arms extending through the eyes 30 of the arms 28 and provided with nuts 31, which when tightened tension the truss rods 26. It will be noted that the right angularly shaped links 29 are at opposite sides of the upper ends of the vertically disposed bolts 2, consequently said bolts will prevent lateral displacement of the links. The nuts 17^a engage the upper sides of the links and if desired may be tightened into close binding engagement with the links after the links have been properly adjusted thereby additionally bracing the same, but at the same time the nuts will not prevent the compressing of the yieldable member 14 by

the crown plate 16 incident to shock or jerking during the oscillation of the beam. It will be noted that the truss rods 26 incline upwardly and inwardly from opposite sides of the ends of the beam and over transversely disposed members 32 which extend beyond the opposite sides of the beam, and which members 32 brace the truss rods and form a bearing point for one side thereof, thereby preventing excessive vibration thereof during the flexing of the beam, and during the compressing and expanding of the yieldable resilient member 14.

One end of the beam is provided with superimposed plates having a yieldable layer of material 33 therebetween, and which plates receive the usual loop and the plates designated by the numeral 34. The yieldable layer 33 additionally absorbs the shock incident to the operation of the beam, consequently relieves the strain to a certain extent on the drilling rig. The other end of the beam 1 is provided with superimposed plates 35 having a layer of yieldable material 36 therebetween, and the end of the beam and plate as well as yieldable material is provided with a slot 37 for receiving the drilling rod or other attachment.

From the above it will be seen that a walking beam is provided for oil well drilling rigs, which beam is positively braced and trussed in a manner whereby it may flex within limits, thereby relieving the sudden jerking strain on drilling mechanism, consequently reducing the possibility of damage to the rig or mechanism to a minimum.

The plates 20 may be additionally held in place by means of tie bolts 40.

The invention having been set forth what is claimed as new and useful is:

1. The combination with a walking beam, a support extending upwardly from said walking beam, a yieldable member on said support, an angularly shaped crown plate on the yieldable member, of tie rods, said tie rods being anchored to opposite sides of the beam adjacent its ends and inclining upwardly and terminating at opposite sides of the crown plate, eyes carried by the inner ends of the tie rods, right angularly shaped links in reverse relation on the crown plate, one arm of the links being threaded, eyes carried by the other arm of said links and through which eyes of the threaded arms of the links extend, nuts threaded on said threaded arms and forming means whereby the links are longitudinally moved, said links extending through the eyes of the tie rods.

2. The combination with a flexible walking beam having an upwardly extending support, a yieldable crown plate on said support, tie rods extending over said crown plate and inclining downwardly and outwardly and anchored to the beam adjacent its ends and members secured to the upper side of the

beam and extending beyond the opposite sides of the beam in engagement with the undersides of the tie rods.

3. The combination with a walking beam, 5 of bracing means for said beam, said means comprising vertically disposed spaced threaded rods carried by the beam, cylindrical members surrounding said rods, a plate engaging the upper ends of the cylindrical 10 members and through which the rods extend, nuts threaded on said rods and engaging the plate, a plate through which the rods extend and in apertures of which the nuts are held, a plate engaging the upper side of the last 15 named plate and having a yieldable member thereon, a crown plate through which the bolts extend and disposed on the yieldable member and tie rods extending over said last named plate and anchored to opposite ends 20 of the beam.

4. A flexible walking beam comprising an elongated member, vertically disposed elongated bolts carried by the elongated member, a plate disposed on said elongated member, 25 cylindrical members disposed on the plate and through which the vertically disposed elongated bolts extend, a plate mounted on the upper ends of the cylindrical members

and on the bolts, nuts on said bolts and engaging the plate, a nut locking plate on the 30 nuts and bolts, a yieldable member on the bolts, a crown plate on said yieldable member and through which the bolts extend, tie rods anchored to the elongated member adjacent its ends and extending upwardly and 35 terminating adjacent the opposite sides of the crown plate, eyes carried by the rods, cooperating links at opposite sides of the bolts, said links extending through the eyes of the tie rods and forming means whereby 40 said rods may be tightened or loosened.

5. The combination with the outer end of a walking beam and downwardly and outwardly extending tie rods terminating at opposite sides of the beam end, of a transversely disposed plate disposed in a recess in the under side of the beam end and extending beyond the opposite sides of the beam end, said tie rods being anchored to the plate beyond the sides of the beam end, and a transversely disposed rib carried by the inner side of the plate and disposed in a channel 50 in the bottom of the recess.

In testimony whereof I hereunto affix my signature.

CHARLES L. LONSINGER.
